US00D853638S

(12) **United States Design Patent** (10) **Patent No.:** **US D853,638 S**
(45) **Date of Patent:** **** *Jul. 9, 2019**

(54) **HAIR STYLING AND HAIR CARE APPARATUS**

(71) Applicant: **Dyson Technology Limited**, Wiltshire (GB)

(72) Inventors: **Benjamin Charles Felix Tappenden**, Bristol (GB); **Britta Jessica Stockinger**, Bath (GB); **Andrea Ee-Va Lim**, Bristol (GB); **Alexander Stuart Knox**, Swindon (GB)

(73) Assignee: **Dyson Technology Limited**, Malmesbury, Wiltshire (GB)

(*) Notice: This patent is subject to a terminal disclaimer.

(**) Term: **15 Years**

(21) Appl. No.: **29/627,741**

(22) Filed: **Nov. 29, 2017**

(30) **Foreign Application Priority Data**

May 30, 2017 (EM) 004024024-0006

(51) **LOC (11) Cl.** **28-03**

(52) **U.S. Cl.**

USPC **D28/18**

(57) **CLAIM**

We claim the ornamental design for a hair styling and hair care apparatus, as shown and described.

DESCRIPTION

The patent or application file contains at least one drawing executed in color. Copies of this patent or patent application publication with color drawings will be provided by the office upon request and payment of the necessary fee.

FIG. 1 is a first side perspective view of a hair styling and hair care apparatus showing our new design;

FIG. 2 is a second side perspective view thereof;

FIG. 3 is a side view thereof;

FIG. 4 is a top view thereof;

FIG. 5 is a bottom view thereof;

FIG. 6 is a front view thereof; and,

FIG. 7 is a rear view thereof.

The view opposite the side view of FIG. 3 is a mirror image thereof, and therefore, is omitted.
